J. C. LYONS, OF NEW YORK, N. Y.

Letters Patent No. 96,020, dated October 19, 1869.

IMPROVEMENT IN THE MANUFACTURE OF HOLLOW-RUBBER GOODS.

The Schedule referred to in these Letters Patent and making part of the same.

To all whom it may concern:

Be it known that I, J. C. LYONS, of New York, in the county of New York, and State of New York, have invented a new and useful Improvement in the Manufacture of Certain "Rubber" Goods; and I do hereby declare the following to be a full, clear, and exact description of the same, reference being had to the accompanying drawings, in which—

Figure 1 is a longitudinal section of my apparatus in operation.

Figure 2 is a perspective view of the same.

Figure 3 is a plan of a single section of India-rubber sheet.

On the 10th day of September, 1867, Letters Patent were issued to me for an improvement in fog-alarms, consisting of a trumpet or whistle, sounded by a current of air under pressure, said compressed air being stored in an expansible air-chamber, made of elastic gum. For this, and other similar purposes, chambers made from sections of hollow elastic cylinders, have been found to be unsatisfactory, in some respects, on account of unequal expansion of said chambers in use; and to obviate these objections I have devised the herein-described mode of forming chambers of elastic gum, with irregular shapes and walls of uniform thickness, and the mode of curing rubber for such purposes.

In the manufacture of hollow India-rubber goods, the exterior formation has been secured by enclosing the India-rubber blank within a metallic mould, and causing the gum to expand and fill the configurations of the mould by means of a small quantity of water enclosed within said blank, and converted into steam by the heat imparted during the vulcanizing-process; or, in some cases, the expansion of the enclosed air is sufficient for this purpose.

India-rubber toys and all similar goods are formed in this way, there being no other known method.

It is evident, however, that in such a case the material will vary in thickness with every variation in its conformation, and this fact will totally unfit any chamber so constructed for any use requiring strength to resist internal pressure.

It has therefore become necessary to devise means of forming India-rubber chambers of irregular shapes and uniform thickness of walls.

In my experiments to this end, no material has been found to afford results so satisfactory as dry, sharp sand, enclosed in a canvas bag of proper form.

My invention, therefore, consists—

First, in the formation of hollow-rubber ware of irregular forms, and walls of uniform thickness, upon a collapsible core.

Second, in the manner of distending said core by means of sharp, dry sand, or its equivalent.

Third, in the employment of a sand-bath in vulcanizing or curing rubber.

Having now set forth the objects and nature of my invention, I will particularly describe the apparatus which I consider most suitable to effectuate said invention, though I desire it to be distinctly understood that I do not limit myself to the exact details, either of manipulation or apparatus described, as both are susceptible of much variation, without in any degree changing the results secured.

A metallic tube, A, forms the nucleus of this apparatus. The canvas bag B, formed in the proper shape, is drawn over said tube, and secured at either end by a cord or wire, C, or in some other convenient and ready method. The short pipe D is introduced at one end of the pipe A for a short distance, and is firmly soldered there, its inner end opening into the space E, between the inner surface of the bag B and the outer surface of the tube A, as shown in fig. 1.

After the canvas bag B has been placed upon the tube A, the ferrules F F are slipped over the ends of the bag B, and the wires or binding, C, are placed upon the extremities of the same, as shown, and sand is poured into the space E, through the pipe D, until said space is filled. A cork or other stopper is then inserted in the end of the pipe D, to prevent any escape of the enclosed sand.

This having been done, the core is ready to receive the raw-rubber covering, which is applied in sheets or blanks, G, cut to pattern, as shown in fig. 2, and particularly in fig. 3. These blanks are cut from sheets of raw or uncured rubber. They are laid upon the mould, and their edges joined by common rubber cement. The whole is then swathed in bandages, H, of canvas or other material, as shown in figs. 1 and 2. These bandages are drawn tight, and are laid smooth over the whole surface of the blanks. The swathing is properly done in the manner known as surgeon-bandaging, by which method a single bandage may be laid smoothly over irregular surfaces.

When the bandaging has been completed, the whole is placed in an oven or hot-air chamber, and the temperature raised to the proper degree to effect the vulcanization of the rubber which is to form the chamber.

The open pipe A admits the hot air of the oven to the interior of the core, and the sand within the space E thereby becomes heated to nearly the same temperature as the surrounding atmosphere, and the heat is thereby transmitted to the inner surface of the rubber shell B, at nearly or quite the same temperature as that which reaches the outer surface of the same through the canvas swathing H. This is an important consideration in the curing of rubber, because the application of moist heat has an effect different from that of dry heat, and the two surfaces of articles

cured in a mould and expanded by steam, have different degrees of elasticity or strength; but with my process of causing the proper internal pressure by means of the expansion of dry sand, and the application of dry heat by transmission through the same substance, the two surfaces have, as nearly as possible, the same qualities, and the strength and elasticity will be uniform throughout.

It may be advisable sometimes to immerse the whole mould in a sand-bath, instead of placing it simply in a hot-air chamber.

When the vulcanizing-process has been completed, the clamps C are removed, and the tube A may then be withdrawn, or the sand may first be discharged through the tube D. When the sand has been discharged, the ferrules F may be withdrawn, and the collapsed canvas bag B may be withdrawn from the inside of the chamber. The swathing-bandages being also removed, the process is complete, and an irregular-shaped hollow chamber, with walls of uniform thickness and elastic strength, has been produced, such as cannot be produced by any other known method.

Having set forth my invention,

What I claim as new, is—

1. A chamber of elastic gum, irregular in shape, and with walls of uniform thickness, and formed over a collapsible core.
2. A core for the above-named purpose, made of canvas or other suitable material, and filled with sharp, dry sand, or its equivalent.
3. The combination of the tube A and sand-bag B to form a hot core for vulcanizing irregular-shaped rubber chambers.
4. The tube A, provided with the feeding-tube D, in combination with the sand-bag B and ferrules F.
5. The herein-described process of forming rubber hollow ware, viz, by placing the raw rubber-blank upon a hollow sand-core, and then swathing the whole with strips of canvas, or other material, as set forth.
6. Curing of rubber ware by the transmission of heat through a sand-bath applied to one or more surfaces of the same.

J. C. LYONS.
